UNITED STATES PATENT OFFICE.

WILLIAM W. LORD, OF RACINE, WISCONSIN, ASSIGNOR TO S. FREEMAN & SONS, OF SAME PLACE.

BROADCAST SEED-SOWER AND FERTILIZER-DISTRIBUTER.

SPECIFICATION forming part of Letters Patent No. 351,988, dated November 2, 1886.

Application filed March 10, 1886. Serial No. 194,685. (No model.)

To all whom it may concern:

Be it known that I, WILLIAM W. LORD, of Racine, in the county of Racine, and in the State of Wisconsin, have invented certain new and useful Improvements in Broadcast Seed-Sowers and Fertilizer-Distributors; and I do hereby declare that the following is a full, clear, and exact description thereof.

My invention relates to broadcast sowers and fertilizer-distributors; and it consists in certain peculiarities of construction, as will be hereinafter described with reference to the accompanying drawings, in which—

Figure 1 represents a rear elevation of my device attached to an ordinary wagon-bed; Fig. 2, a plan view of the same; Fig. 3, a detail view of the shifting-lever and socket detached; Fig. 4, an under side view of Fig. 3 with the parts operatively connected; Fig. 5, a detail perspective view of the distributor; Fig. 6, a longitudinal vertical section of my device on line *x x*, Fig. 1; Fig. 7, a detail view showing the bearing for the upper end of the distributor-shaft; Fig. 8, an under side view 25 of the hopper, &c.; and Fig. 9, a detail perspective view of a portion of the plunger and its connecting-lever.

Referring by letter to the drawings, A represents the forward or horizontal portion, and B the vertically-depending or rear portion, of the hopper of my sower. The forward portion, A, of the hopper, that forms a receiving-box for the material to be sown, is intended to rest upon the bottom of a wagon-body, C, at one side thereof, and be detachably secured to said wagon-body in any suitable manner. The vertical portion or delivery-box B of the hopper extends outside the rear end of the wagon-body, and is designed to support the operative 40 elements of the sower.

To facilitate the flow of the material to be sown toward the vertical or delivery portion B of the hopper, the horizontal part A thereof is provided with an inclined bottom, *a*, and to enable the operator to have access to the lower interior portion of said hopper I provide the latter's rear side with an opening, *a'*, designed to be closed by a slide, *a''*. The vertical portion B of the hopper has its top *b* and rear side,

50 *c*, cut away to receive a segmental shell, D, that is provided with a continuous angular

flange, *d*, designed to bear against the exterior of said hopper and be secured thereto by suitable bolts.

The main interior portion of the shell D 55 forms a housing for a main gear-wheel, E, keyed to a shaft, F, that is journaled in bearings *ff'*, respectively secured to the angular flange *d* and to a projection, *g*, of the hopper-top *b*, said flange being provided with lugs *h*, between 60 which the bearing *f* is seated, to prevent its longitudinal displacement. One side of the shell D is offset at *i* to form a housing for a pinion on the upper end of a distributor-shaft, H, said pinion being arranged to mesh with the 65 gear-wheel E, and the distributor-shaft provided with a stirring-pin, *m*.

The upper end of the distributor-shaft H is reduced, as shown at *k*, and this reduced portion thereof has its bearing in a bushing, *n*, 70 forming a part of a plate, I, that is bolted to the bottom of the shell D near its rear end. The bushing *n* of the plate I extends in a downward direction to fit within a perforation, *o*, 75 in the bottom of the shell D, the diameter of this perforation being slightly greater than that of the distributor-shaft, so as to readily admit the passage of the latter to its lower bearing in the hopper-bottom K.

By the construction just described and illustrated in detail, Fig. 7, I facilitate the setting up of the machine and form a strong bearing for that point of the distributor-shaft on which comes the greatest strain, and at the same time I accomplish a saving in the metal forming the 85 shell D.

The hopper-bottom K is provided with openings *p* for the passage of the material to be sown, and between this bottom and a guide-plate, M, bolted thereto is operatively secured 90 a gage-plate, N, having openings *r*, designed to register with those in said hopper-bottom.

It is intended that each machine shall be accompanied with a series of interchangeable gage-plates, the openings therein being graduated, so as to readily adapt the machine to the sowing of different varieties of seed and grain, and each plate is held in operative position by a spring-key, *s*, passing through it and said guide-plate.

100 The distributor is preferably composed of four overlapping irregular-shaped sections of

sheet metal secured to each other and the flange *t* of a hub, *P*, the latter being rigidly connected to the shaft *H*. Each of the sheet-metal sections composing the distributer has its edge 5 *u* curled up and over in such a manner as to form a semi-cylindrical face radial to the shaft *H*, and extended beyond the straight edge *u'* of the adjacent underlapping section, the greatest curl of said edge *u* being at the outermost 10 point.

This construction results in a comparatively inexpensive distributer that gives an even and thorough cast to the seed or other material to be sown, and at the same time cheapens the 15 construction of the machine.

Secured to a rod, *Q*, that passes through the bottom *K*, outside the hopper, is a triangular cut-off plate, *R*, provided with openings *v*, designed to be brought in or out of register 20 with those in said hopper-bottom and gage-plate *M*. The rod *Q* has its upper end fast to a shifting-lever, *S*, that is retained in its adjusted position by a segmental rack, *T*, bolted to the top *b* of the hopper, and designed to engage a lug, *w*, projecting from the under side 25 of said lever. This rack *T* has its flange *y* provided with slots *y'*, and is thereby readily adjusted to compensate for the lost motion that may be variously occasioned in the adjacent 30 relative mechanism, thus always providing for the proper operation of the cut-off plate *R*.

The shifting-lever *S* is preferably composed of a blade of spring-steel seated in a casting, *S'*, that fits upon the rod *Q*, and has a reduced 35 part, *b'*, that is provided with lugs *c'*. This reduced portion of the casting *S'* is designed to fit a bracket, *S''*, bolted to the flange *d* of the part *D*, and having recesses *d'*, to admit the 40 passage of the lugs *c'*. When the casting *S'* and the bracket *S''* are in operative position, the lugs *c'* come under against said bracket and prevent any dislocation of the parts.

Secured to the top *b* of the hopper is a right-angled bracket, *U*, having its base provided 45 with a rectangular opening, *e*, and within this opening are journaled friction rollers *e'*. Passing between the friction-rollers *e'*, and on down through the hopper-top, is a plunger, *V*, provided on its lower end with a series of lateral 50 projections *g'*, and pivotally connected at its upper end to an arm, *W*, the trunnions *h'* of which latter are journaled in the bifurcated end *i'* of the vertical portion of the bracket *U*. The arm *W* is connected by a link, *X*, to 55 a pin, *k'*, extended from the inner face of the gear-wheel *E*, and by this connection a reciprocative motion is transmitted to the plunger *V*. This plunger acts to increase the agitation 60 of the material in the hopper and prevents the same from packing so as to clog up the delivery-openings, and thereby seriously affect the successful operation of the machine. When the machine is used for distributing 65 fertilizers, the plunger is especially valuable, as in such instances, but one opening only being employed for the delivery of the material, said plunger is so arranged that its down-

stroke will finish in line with this opening, and thus tend to force said material through the same, the projections *g'* constantly cutting 70 and disintegrating the mass while the machine is in operation.

The shaft *F* is provided with the usual loose sprocket-wheel, *F'*, having one side thereof provided with teeth to engage a clutch, *F''*, rigid on said shaft. An angular spanner-arm, *Y*, embraces the hub of the sprocket-wheel, and is secured thereon between collars *m'*. The spanner-arm is adjustably connected to a shifting-lever, *Z*, pivoted to casting *Z'*, 80 that is secured to the hopper-top *b*, and provided with a depression, *n'*, to engage the forward portion *Z'* of said lever, this latter part being composed of spring-steel.

Interposed between the bearing *f'* and hub 85 of the sprocket-wheel *F* is a spring, *G*, coiled about the shaft *H*, and when the shifting-lever is operated to disengage the clutch mechanism this spring is compressed. The forward portion, *Z'*, of the shifting-lever being of 90 spring-steel, only a slight upward pressure is necessary to disengage it from its catch, and when such operation takes place the expansive force of the spring *G* causes an immediate automatic engagement of the clutch-teeth on the 95 sprocket-wheel *F'* with the clutch *F''*. The sprocket-wheel *F'* is intended to be geared in the usual manner to one of the rear wheels of a wagon, and from this source the motive power is derived for operating the sower. 100

Having thus fully described my invention, what I claim as new, and desire to secure by Letters Patent, is—

1. A broadcast sower having its hopper composed of a forward horizontal receiving-box adapted to be secured within a wagon-body, and a rear vertical depending delivery portion designed to extend out from said wagon-body and support the operative elements of the device, as set forth. 105

2. A broadcast sower having its hopper composed of a forward horizontal portion provided with an inclined bottom, and adapted to be secured within a wagon-body, and a rear vertically-depending portion designed to extend out from said wagon-body, and having one of its sides, near the bottom thereof, provided with a covered opening, said vertical portion of the hopper also forming a support for the operative elements of the machine, as 115 set forth. 120

3. A broadcast sower having the vertical portion thereof provided with a segmental shell forming a housing for the main gear-wheel and the pinion on the distributer-shaft, 125 as set forth.

4. A broadcast sower provided with a shell having a continuous angular flange and adapted to fit within a cut-away portion at the upper rear end of the hopper, the main inferior portion of the shell forming a housing for the main gear-wheel, and one side of said shell offset to form a housing for a pinion on the distributer-shaft, as set forth. 130

5. A broadcast sower having a segmental shell set in the upper rear end of the hopper and adapted to form a housing for the main gear-wheel and distributer-shaft pinion, the 5 bottom of said shell provided with a perforation, and a plate adapted to be secured to the shell-bottom, and having its forward ends formed with a downward-extending bushing designed to fit the perforation in said shell- 10 bottom and the reduced upper end of the distributer-shaft, as set forth.
6. A broadcast sower having the distributer thereof composed of overlapping irregular-shaped sections secured to a suitable hub, and 15 one edge of each section curled up and over to form a semi-cylindrical face radial to the center of the distributer-shaft and extended beyond the straight edge of the adjacent un- 20 derlapping part, as set forth.
7. A broadcast sower having the distributer thereof composed of overlapping irregular sheet-metal sections secured to a suitable hub, and 25 one edge of each section curled up and over to form a semi-cylindrical face radial to the center of the distributer-shaft and extended beyond the straight edge of the adjacent un- 30 derlapping part, as set forth.
8. A broadcast sower having the distributer thereof composed of overlapping irregular-shaped sections secured to a suitable hub, each section having one of its edges curled up and 35 over to form a semi-cylindrical face radial to the center of the distributer-shaft, with the greatest curl at the outermost point, as set forth.
9. A broadcast sower having a triangular 40 cut-off plate provided with openings adapted to be brought in and out of register with the discharge-openings in the hopper-bottom and seed-plate, a vertical rod connected to said cut-off plate, and a shifting-lever in turn connected to the rod, in combination with a segmental rack adjustably secured to the hopper-top to engage the lever, as set forth.
10. A broadcast sower having a triangular 45 cut-off plate pivotally connected to a vertical shifting-rod and provided with openings adapted to be brought in and out of register with the discharge-openings in the hopper-bottom and seed-plates, as set forth.
11. A broadcast sower having the shifting- 50 lever for the cut-off rod composed of a spring-steel blade seated in a casting adapted to fit said rod, and said casting provided with a reduced portion adapted to fit a suitable bearing, as set forth.
- 55 12. A broadcast sower having the shifting-lever for the cut-off plate composed of a spring-steel blade provided with a depending lug and seated in a casting having a reduced portion adapted to fit the cut-off rod, and provided 60 with lugs, in combination with a bracket designed as a bearing for the reduced portion of the lever and provided with recesses to admit the passage of the lugs on said reduced portion of the lever, and an adjustable rack adapted to engage the depending lug of the spring- 65 blade, as set forth.
13. The combination, in a broadcast seed-sower, of a stationary hopper, a vertically-reciprocating plunger having projections g , the driving-shaft, and connections through 70 which the plunger is reciprocated by the driving-shaft, as set forth.
14. A broadcast sower provided with a plunger designed to operate within the hopper thereof, an arm connected at one end by a 75 link and pin to the main gear-wheel of the machine, and an angular bracket forming a bearing for the arm and a guide for the plunger, as set forth.
15. A broadcast sower having its hopper-top provided with an opening, an angular bracket adapted to be secured to the hopper-top, and also provided with an opening designed to register with the one in said top, and friction-rollers journaled in the bracket-opening, 80 in combination with a plunger operative between the friction-rolls and depending into the hopper, an arm having a link-connection with the main gear-wheel and pivotally secured to the upper end of the plunger and 85 bracket, as set forth.
16. A broadcast sower having an opening in its hopper-top, a right-angular bracket having an opening in its base adapted to register with the one in the hopper-top, and the upper end of the vertical portion of said bracket bifurcated to form bearings for the trunnions on an arm having one end thereof linked to the main gear-wheel, and friction-rollers journaled in the opening of the bracket-base and 90 designed as guides for a plunger pivoted to the suspended arm and depending into the hopper, as set forth.
17. In a broadcast sower, a clutch-faced 95 sprocket-wheel loose on a driving-shaft and operatively connected to a spanner-arm, and a spring coiled about the shaft to automatically actuate said sprocket-wheel, whereby an automatic engagement is had with a fixed clutch on said shaft, in combination with a 100 spring-steel lever adjustably united to the spanner-arm and designed to engage a suitable casting secured to the hopper-top, as set forth.
- In testimony that I claim the foregoing I have hereunto set my hand, at Louisville, in 105 the county of Jefferson and State of Kentucky, 110 in the presence of two witnesses.
